United States Patent Office

Des. 185,755
Patented July 28, 1959

185,755

CARRIER FOR OUTBOARD MOTOR

John W. Klages, Columbus, Ohio, assignor to The Columbus Auto Part Company, Columbus, Ohio, a corporation of Ohio

Application March 17, 1959, Serial No. 55,026

Term of patent 14 years

(Cl. D14—3)

Fig. 1 is a side view of a carrier for outboard motor showing my new design;

Fig. 2 is a rear view thereof;

Fig. 3 is a side perspective view thereof; and

Fig. 4 is a top view thereof.

I claim:

The ornamental design for a carrier for outboard motor, substantially as shown.
